UNITED STATES PATENT OFFICE.

WINIFRED C. UTLEY, OF MILWAUKEE, WISCONSIN.

PAPER-PERFORATING MACHINE.

SPECIFICATION forming part of Letters Patent No. 267,780, dated November 21, 1882.

Application filed June 12, 1882. (No model.)

To all whom it may concern:

Be it known that I, WINIFRED C. UTLEY, of Milwaukee, in the county of Milwaukee, and in the State of Wisconsin, have invented certain new and useful Improvements in Perforating-Needles for Making Patterns and Designs on a Sewing-Machine; and I do hereby declare that the following is a full, clear, and exact description thereof.

My invention relates to devices for producing paper stencils for marking embroidery designs and other patterns, names, initials, &c., on cloth, and is adapted for use in connection with sewing-machines, as will be more fully set forth hereinafter.

In the drawings, Figure 1 represents in perspective a portion of a sewing-machine with my device in position for use. Fig. 2 is an enlarged view of the preferred form of my perforating-needle. Fig. 3 represents a paper stencil produced by the use of my device, and ready for transfer of the pattern; and Fig. 4 is a view of a modified construction of my needle, much enlarged.

A designates an ordinary throat-plate—such, for instance, as is found on the "Household" and "Domestic" sewing-machines—and which is attached to the machine by a screw, and has a slot just over the feed. B is the needle-bar, and B' the bar that carries the presser-foot. All these parts are of any ordinary construction, and form no essential part of my invention, except so far as their use is required in the operation of my device.

C is my perforating-needle. It consists of shank *a* (similar to the shanks of ordinary sewing-machine needles) and stem *b*, and is preferably beveled, as shown in Fig. 2, at the end *c*. In the plate A is the hole D, which must be of the exact shape of the cross-section of the stem *b*, and of corresponding size, so that the said stem may pass in and out of the hole D, close to the walls of said hole, as the needle-bar is vertically reciprocated, whereby the needle C may have a punching action, and make a clean cut through the paper, punching a little hole with each reciprocation of said needle. The presser-foot holds the paper against the plate and enables it to be guided by hand in any direction without slipping. I find that the needle C makes the cleanest cut

when its end *c* is beveled. Hence I prefer that construction, but it will work satisfactorily if the end is perfectly flat or square, as represented in Fig. 4.

E designates a sheet of paper containing a pattern or design consisting of a number of minute perforations, *e e e*, produced by my device, and constituting in effect a paper stencil-plate. These perforations are of about one-half the preferred size, the needles being here shown in exaggerated size, the better to exhibit their construction; but for coarse work my needles may be of any size desired. The design is first traced or marked, say, with a lead-pencil, on the sheet, and then my needle C having been adjusted to the needle-bar of a sewing-machine directly over the hole D in the plate, the presser-foot is brought down over the paper laid on the plate and the machine started. It requires very little practice to follow the lines marked on the paper, and thus in a short time the said lines are completely covered by the minute holes *e e* punched out by the needle. The sheet E can then be laid upon the cloth to be worked or embroidered, and by means of a pad or brush and suitable liquid or powder the exact design or pattern can be transferred to the cloth. This operation may be repeated as often as necessary, moving the stencil along to complete the design.

It will require less care in adjusting the needle to its place on the needle-bar if the stem *b* is round in cross-section, as in that case the needle will readily pass into and out of the hole D, no matter which way the said needle is turned; but I do not limit myself to a needle with stem round in cross-section, as one square, triangular, or even irregular would answer as well, (or any other shape,) it being only necessary that the stem *b* and hole D exactly correspond to insure good work and a clean cut, without any of the paper being turned downward at the edges of the perforations *e e*, as would happen if my needle was pointed in the ordinary manner. This I have discovered by actual experiment, and discarded that form of needle-point. If different-sized perforations are required, an equal number of plates, or a movable plate with series of holes of different sizes, will be required, so that there may be the proper-sized hole D to each size of needles.

Although I have shown my device in connection with a "Household" or "Domestic" sewing-machine plate, it is apparent that it is adapted for use on any other sewing-machine that has a vertically-reciprocating needle-bar, the one essential feature being correspondence in size and shape between the stem of my needle and the needle-hole in the plate.

I prefer to make my needle with a solid stem, 10 beveled or flat at the lower end, *c*, because this construction is the simplest and cheapest, and one that works perfectly; but of course it would work just as well if there was only a ring or circular cutting-edge on the end of the needle 15 formed by drilling out the stem; but this would be much more costly, and would not work any better, as the paper punched out by my device does not interfere with the working parts of the sewing-machine.

Having thus described my invention, what I 20 claim as new, and desire to secure by Letters Patent, is—

In combination with the presser-foot, vertically-reciprocating needle-bar, and feed of a sewing-machine, the plate A, having hole D, 25 and the perforating eyeless needle C, the diameters of the stem of the said needle and the said hole D corresponding exactly to each other, as set forth.

In testimony that I claim the foregoing I 30 have hereunto set my hand on this 5th day of June, 1882, in the presence of two witnesses.

WINIFRED C. UTLEY.
